CLARENCE E. LOMAX, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed January 18, 1926, Serial No. 81,900. Renewed May 24, 1928.

This invention relates to automatic telephone systems in general, but is more particularly concerned with trunking arrangements between a main automatic exchange and a private branch exchange. The object of this invention is the provision of a new and improved trunking arrangement for the trunking between a main automatic exchange and one or more private branch exchanges especially adapted for use when several private branch exchanges are each accessible from the main automatic exchange by large number of trunks. Another object of the invention is the provision of new and improved automatic switches especially adapted for use in conjunction with the new trunking arrangement, however not being limited to such use.

A well known trunking arrangement employed for trunking between a main automatic exchange and private branch exchanges is that in which trunks from the banks of a group of rotary connectors at the automatic exchange terminate at the operators' switchboards at the private branch exchanges, the trunks to each private branch exchange being accessible in a certain level of the rotary connector banks. The rotary connectors in turn are accessible in a particular level of the banks of a certain group of selectors.

When the number of P. B. X.'s (the abbreviation P. B. X. will hereafter be used for "private branch exchange") accessible from the M. A. X. (the abbreviation M. A. X. will hereafter be used for "main automatic exchange") approaches ten and when the number of trunks to these P. B. X.'s approaches ten, it may become economical to use one-digit connectors for the rotary connectors. In each level, then, access is had to the trunks to one certain P. B. X. In this case, the corresponding contacts in each level of all the rotary connectors are multiplied together, thus providing ten trunks to each P. B. X. accessible in the level assigned to that P. B. X. If a P. B. X. requires more than ten trunks to take care of its traffic, the number approaching twenty-five trunks, the corresponding bank contacts of all the connectors are not multiplied together. The connectors as regards this level, are sub-divided into several groups, the corresponding contacts of the

connectors in each sub-group being multiplied according to the well known practice, thereby increasing the number of outgoing trunks. 55

According to the well known trunking arrangement, each trunk from connector banks, instead of being connected directly to an outgoing trunk to the P. B. X. in question, may terminate in a rotary line-switch. The banks of all of these line switches may then be multiplied together, 60 so that each rotary lineswitch has access to all the trunks to the P. B. X. in question. For further explanation, a particular case may be considered: A certain P. B. X. may require twenty-five incoming trunks from 65 the main automatic exchange to carry the traffic. It may be supposed that in order to give a required trunk hunting efficiency under the existing traffic conditions, one-digit connectors are provided and, as regards the level assigned to this P. B. X., are divided into four sub-groups, the corresponding bank contacts in each sub-group being multiplied together and connected to trunks terminating in line switches, each 70 rotary line switch having access to the twenty-five trunks to the P. B. X. The one-digit connectors may be accessible in a certain level of one group of selectors. When a 75 call is extended to a one-digit connector, which is then operated to connect with an idle trunk in the level in question, the call under all possibilities will be extended via an outgoing secondary line switch to a 80 trunk to the P. B. X., providing there is at least one of the twenty-five trunks to the P. B. X. idle. To give this efficiency of 85 trunk selection in the present assumed case, however, forty line switches are required, one for each of ten trunks from each of the four sub-groups of connectors. 90

A feature of this invention, however, is the disclosure of a scheme whereby the number of secondary line switches in a case, such as assumed, can be greatly reduced 95 without lowering the trunk selecting efficiency any significant amount. According to this invention it is proposed, instead of connecting each of the ten trunks of each sub-group of connectors as regards the level in question to a rotary line switch, to connect only the last few trunks of each sub-group to rotary line switches, and connect 100

the first several trunks directly to outgoing trunks to the P. B. X., still giving the rotary line switches access to all the trunks to the P. B. X. With this new arrangement in all but the more busy times of the day, the calls over each sup-group of connectors would be trunked directly to the P. B. X., and only during the more busy periods, when the number of calls in any one 10 sub-group of connectors approached ten, calls would be trunked to the P. B. X. via rotary line switches. Furthermore, if the traffic load is kept reasonably well distributed between the different sub-groups, to the 15 extent, for instance, that when ten simultaneous calls exist in some one sub-group there will be substantially as many calls in each of the remaining sub-groups as there are direct trunks to the P. B. X. from each sub- 20 group, no sacrifice in trunk hunting efficiency will be made, the new arrangement then giving the same efficiency as in the case when all the trunks from the connector banks are connected to rotary line switches. 25 This arrangement may be more explicitly described and its advantages explained by referring to the accompanying drawings, Figs. 1 to 4, inclusive.

Figs. 1 and 2, when Fig. 2 is placed to the 30 right of Fig. 1 with the corresponding lines in alignment, is a trunking diagram of part of the particular telephone system partially described in the preceding paragraphs, which illustrates the new trunking arrangement proposed according to this invention. Figs. 3 and 4, when Fig. 4 is placed to the 35 right of Fig. 3 with the corresponding lines in alignment, show by means of the usual circuit diagrams the various automatic switches and the circuits at a P. B. X. through which a call may be extended from a M. A. X. to a P. B. X.

Referring now to the trunking diagram, Figs. 1 and 2, the assumption is made that 45 the P. B. X. referred to previously as well as several other P. B. X.'s are accessible via trunks in one level of a certain group of selectors. This group of selectors is divided into twenty sub-groups. This division is 50 diagrammatically indicated at the extreme left of Fig. 1, only seven of the twenty sub-groups being shown. The first five trunks from each of the twenty sub-groups of selectors are connected directly to one-digit 55 connectors making a total of 100 one-digit connectors accessible directly from selectors. The last five trunks of each sub-group of selectors terminate in plunger type line switches through an intermediate distributing frame designated IDF, thus utilizing a total of 100 plunger line switches. The one digit connectors are mechanically of the well known Strowger step-by-step type, and are responsive to one series of impulses to 60 raise their wipers opposite the correspond-

ing level of bank contacts, and perform an automatic rotary operation to select an idle trunk in that level. The plunger line switches are also similar mechanically to the well known Keith type of line switch, differing in circuit arrangements as will be described fully in later descriptions. 70

A total of 140 one-digit connectors have been provided to carry the traffic to the several P. B. X.'s in this telephone system. 75

With 100 of the one-digit connectors accessible directly from selectors, the remaining forty connectors are made accessible via plunger line switches. Since the plunger type line switch has a capacity of only ten 80 outgoing trunks, and since forty connectors are accessible via plunger line switches, the total of 100 line switches are divided into four groups of twenty-five line switches each, each group having access to ten one-digit connectors. The usual cross-connecting scheme may be carried out at the IDF so that in each of the twenty sub-groups of selectors, each of the five outgoing trunks 85 has access to a different group of ten one-digit connectors as far as possible. 90

Only the level of one-digit connectors assigned to the P. B. X. to be considered is shown. As described previously, it has been assumed that four groups of ten trunks each are required from this connector bank level to carry the traffic via twenty-five outgoing trunks to the P. B. X. being considered. Therefore, the total of 140 connectors as regards this level is divided into four groups of thirty-five connectors each, twenty-five accessible directly from selectors, and ten from plunger line switches constituting one group. The corresponding bank contacts of the connectors of each group are multiply 100 connected. As previously mentioned, the bank multiplying of the connectors may differ in the various levels, but since there are four groups of plunger line switches and further since there are four groups of ten trunks 105 each outgoing from the one-digit connectors from the level under consideration, the connectors themselves have been shown in four groups, thereby simplifying the drawings. 110

In the case illustrated, the first six trunks from the connector banks of each group of connectors are connected directly to the outgoing trunks to the P. B. X. while the last four trunks of each group of connectors are each connected to a rotary line switch. The 115 rotary line switches are mechanically of the well known type of rotary step-by-step switch having twenty-five sets of bank contacts, and in this case a set of busy contacts, and which, at the termination of each call, rotates back to normal or its home position. The circuit details of these rotary line switches form part of this invention and will be fully described in later descriptions. 120

A graded multiple scheme between the 125 130

- trunks from the four groups of connectors connected directly to the outgoing trunks has also been carried out as shown in the illustration. The first and second trunks of each group are each connected directly to an outgoing trunk to the P. B. X. in question; the third trunk and the fourth trunk of the first and second group and of the third and fourth group are multiplied together respectively, and connected to separate outgoing trunks; while the fifth trunk and the sixth trunk of the four groups are multiplied together and connected to separate outgoing trunks.
- 5 To prevent the outgoing trunks connected directly to trunks from the connectors from being seized by the rotary line switches except under extreme traffic conditions, the rotary line switches being of the home position type, the said trunks are made last choice to the line switches.
- The corresponding bank contacts of the four rotary line switches terminating the four trunks from a group of connectors are 25 multiplied together and connected to the outgoing trunks. The multiplying between the four groups of rotary line switches is clearly indicated in the drawing and need not be further discussed.
- 30 The trunking scheme between the selectors and the one-digit connectors, i. e., the connecting of the first several trunks directly to connectors and the remaining trunks to line switches having access to other connectors, 35 is not new, but is shown in this case to illustrate how this scheme can be used in a system such as assumed, and also to compare this scheme with the new trunking scheme between trunks from the connector banks and 40 the outgoing trunks, i. e., the connecting of the first several trunks from the connector banks directly to outgoing trunks and the remaining trunks from the connector banks to rotary line switches having access to all 45 the trunks to the P. B. X. including those accessible directly from the connectors.
- Referring now to the circuit diagrams, Figs. 3 and 4, at the extreme left of Fig. 3 are shown three rows of bank contacts of a 50 certain level of the first sub-group of selectors, corresponding to the ten terminals, selector sub-group 1, shown in Fig. 1. The trunk comprising conductors 5', 6' and 7' accessible at the first set of bank contacts 2', 55 3' and 4', (designated V' in Fig. 1) terminates in the one-digit connector C' which is one of the 25 connectors of group 1—A shown in Fig. 1. The trunk comprising conductors 5, 6 and 7 accessible at the sixth set 60 of bank contacts 2, 3 and 4, (designated V in Fig. 1) terminates at the IDF where it is connected to the trunk comprising conductors 8, 9 and 10, the latter trunk terminating in the plunger line switch PLS. The line 65 switch PLS is one of the 25 plunger line switches of group 1 in whose banks access is had to the ten one-digit connectors of group 1—B. Connector C accessible at the bank contacts 21-24, inclusive, of line switch PLS is one of the one-digit connectors of group 70 1—B.
- Only the level of bank contacts of the connector C and of the connector C' in which access is had to the P. B. X. to be considered is shown. It is understood, of course, that 75 the Strowger step-by-step automatic switch usually has banks consisting of ten horizontal rows or levels of ten sets of contacts each. In the level in question as previously explained, the first six sets of contacts of connectors C' and C (multiplied with the other connectors of groups 1—A and 1—B) are connected directly to outgoing trunks to the P. B. X., while the last four sets of contacts of connectors C' and C (multiplied with 80 the other connectors of groups 1—A and 1—B) terminate in rotary line switches. Thus the first set of bank contacts 74', 75', and 76' of connector C' (designated X¹ in Fig. 1) and the first set of bank contacts 74, 75, and 76 of connector C (designated X in Fig. 1) are multiply connected to conductors 91', 92' and 93' (designated Z' in Fig. 1 and Fig. 2), respectively. The conductors 91' and 93' are connected to the outgoing trunk conductors 101 and 102 which terminate at the private branch exchange in jack J. The seventh set of bank contacts 77', 78', and 79' of connector C' (designated Y' in Fig. 1) and the seventh set of bank contacts 77, 78, and 79 of connector C (designated Y in Fig. 1) are multiply connected together to conductors 91, 92, and 93 (designated Z in Fig. 1 and Fig. 2), respectively, the latter three conductors terminating in the rotary line 105 switch RLS. The line switch RLS is one of the four rotary line switches of group No. 1 shown in Fig. 2, in whose banks access is had to all the outgoing trunks to the P. B. X. Each trunk terminates in a jack such as jack J at the P. B. X. Since the trunk comprising conductors 101 and 102 is first choice to the connectors of group No. 1, it is made last choice to the rotary line switch, as described previously.
- The interconnecting trunks from the M. A. X. to the P. B. X. may be two-way trunks. In this case, each trunk will also terminate in a line switch at the M. A. X. These line switches may also be of the rotary type similar to the line switch RLS, preferably having no normal position, however, and the circuit differing in that respect. As indicated in Fig. 4, conductors 91² and 93² connected to conductors 101 and 102, respectively, and 110 private conductor 92² terminate in a rotary line switch RLS'.
- The operator's position is provided with one or more cords such as cord O, having an answering plug P and a calling plug P'. 130

The circuit of this cord is new and simplified, being practically the same for both ends. Associated with the cord O is the telephone set TS and the calling device S. The lines from the P. B. X. substations terminate in jacks such as jack J' terminating the line comprising conductors 161 and 162 of the substation A.

In a system in which connection may be established from subscribers in a main automatic exchange to subscribers in a manual branch exchange over two-way trunks, the operator at the branch exchange may not always be able to remove the connecting plugs immediately after the subscribers replace their receivers at the completion of a call. It is desirable, however, that as many as possible of the switches at the automatic exchange be released immediately after the calling subscriber replaces his receiver, independent of the operator at the branch exchange. If all the switches associated with a certain connection were released immediately upon the replacement of the receiver by the calling party with the operator's plug still in the jack of the trunk used, a needless operation of the line switch connected to this trunk at the automatic exchange and a first selector would result by reason of the bridge across this trunk in the operator's cord. This needless operation is ordinarily prevented by employing release-by-last-party connectors of a type which do not release until the operator removes the plug from the jack of the trunk used, but which momentarily remove ground from the release conductor as soon as the calling party replaces his receiver to permit the preceding switches to restore to normal. The reapplication of ground on the release conductor prevents a connector held operated from being seized until after it is again released following the removal of the plug from the jack of the trunk used.

The introduction of the plunger line switches between the selectors and the one-digit connectors creates a special problem. Without employing some special means of prevention, the plunger line switch associated with a connection would be released as soon as ground was removed from the release conductor. The release of the line switch would immediately destroy the metallic connection back to the selector banks. Bearing in mind that a plunger line switch stands opposite the trunk last used until the controlling master switch has made a complete oscillation, it is evident that the trunk to this plunger line switch in question might be seized in the establishment of a second connection and cause this plunger line switch to again connect to the connector which may still be in an operated position. The second attempted connection in this case obviously would not be completed.

The circuits of the one-digit connector and the plunger line switch used have been so designed as to eliminate this possibility, this constituting another feature of this invention. When the subscriber at the M. A. X. replaces his receiver at the end of a call, the one digit connector used functions to permit the release of the preceding selector switches, but maintains itself and the associated plunger line switch in an operated position until the P. B. X. operator removes the plug from the jack of the trunk used. With both the one-digit connector and the plunger line switch held in an operated position, the trunk terminating in that line switch will be marked busy, and no selector will seize this trunk when so marked. As soon as the operator removes the plug from the jack, the connector and the plunger line switch are restored and the associated trunk is again available for other connections.

The objects of the invention as expressed above and the features of the invention, those mentioned and others not specifically stated, are described in the following descriptions of the operation of the various switches through which a call may be extended under various conditions. For this purpose it is first assumed that a subscriber at the automatic exchange wishes to establish a connection with the subscriber at substation A of the P. B. X. and that the traffic is heavy at the time. To initiate the call, the subscriber at the automatic exchange removes his receiver and dials the directory number assigned to the P. B. X. in question. In response to the removal of the receiver and the dialling of the first one or more digits (the number depending on the size of the automatic system), automatic switches are successively operated to extend the connection to an idle selector in a sub-group of selectors having access to the trunks to this P. B. X., which may be assumed to be the sub-group 1. In response to another digit dialled, this selector operates to elevate its wipers opposite the proper bank contacts and then rotates its wipers in search for an idle trunk. Since it has been assumed that the traffic at this time is rather heavy, it may be further assumed that the first five trunks accessible in the banks of this selector are busy and the first trunk idle at this time is the trunk accessible in the sixth set of bank contacts connected to the terminals 2, 3, and 4, inclusive, terminating the trunk comprising conductors 5, 6, and 7, shown in Fig. 3. Upon the seizure of this trunk by the selector, ground potential is placed upon the private bank contact connected to the terminal 3, closing a circuit which may be traced from ground supplied to the terminal 3, trunk conductor 6, jumper 9', conductor 9, through the pull down winding 11 of the plunger line switch PLS, closed contacts 13

to the main battery supplied to conductor 13' at the master switch (not shown). The pull down winding 11 energizes and causes the operation of the plunger arm 15. The 5 operation of the plunger arm 15 causes the separation of contacts 13 and closes contacts 14, thereby closing a holding circuit for the pull down winding which now includes resistance 16. The operation of the plunger 10 arm also forces the bank springs 17-20, inclusive, into engagement with the bank contacts 21-24, inclusive, respectively, it being assumed that the plungers of the idle line 15 switches of the group containing the line switch PLS have been standing opposite this set of bank contacts. Ground potential is now supplied to the conductor 29' from terminal 3, via bank spring 19 and bank contact 23, terminating in the master switch 20 bank. This causes the master switch to operate and position the remaining idle line switch plungers opposite the next idle trunk in the well known manner.

By the engagement of bank springs 18 25 and 20 with bank contacts 22 and 24, respectively, a circuit is closed which extends from the bridge at the calling subscriber's substation and the two talking conductors extending through the various automatic 30 switches to terminals 2 and 4, conductors 5 and 7, jumpers 8' and 10', conductors 8 and 10, bank springs 18 and 20, bank contacts 22 and 24, conductors 28 and 30, normally closed springs controlled by armatures 42 35 and 43, through the upper and lower windings of line relay 32 to battery and ground, respectively, ground being supplied to the lower winding at the closed springs 64. Line relay 32 operates and closes a circuit 40 for release relay 33 at armature 45 and the working contact. Release relay 33 operates and prepares a circuit for the vertical magnet 38, which includes the series relay 34, at armature 48 and the working contact. At 45 armature 47, ground is supplied to the release conductor 29 to guard the trunk connected to the terminals 2, 3, and 4, from being seized by another switch, and also to maintain the previously operated switches 50 in position, this ground being supplied before the release relay in the preceding selector has had time to fall back, as is well known in the art. Ground on the conductor 29 also serves to maintain the pull-down 55 winding 11 energized. At armature 46, ground is supplied to the conductor 27, thereby closing a circuit for the auxiliary holding winding 12. The function of this auxiliary holding circuit will become evident 60 in a later description. The connector C is now prepared to receive the impulses produced by the dialling of the next digit.

In response to the impulses produced by the dialling of the next digit, line relay 32 deenergizes and again energizes a corre-

sponding number of times. Each time the armature 45 drops back, a circuit is closed for the vertical magnet 38. The purpose of the resistance 68 shunting armature 61 will be explained subsequently. In response 70 to the operation of the vertical magnet 38, the wipers 71, 72, and 73 are raised step-by-step opposite the level corresponding to the digit dialled. The series relay 34 is also energized in series with the rotary magnet 38 and functions in conjunction with the springs 66 which are closed upon the first vertical step of the switch wipers to close the initial circuit for the stepping relay 36. This circuit may be traced from ground at 75 armature 46 and the working contact, armature 59 and the resting contact, armature 50 and the working contact, springs 66, through the winding of the stepping relay 36 to battery. Relay 36 operates and closes 80 a temporary holding circuit for itself at armature 55, and prepares a circuit for the rotary magnet 39 at armature 56. Relay 34 is slow acting and therefore remains energized during the entire vertical movement. 85 At the end of the vertical movement, series relay 34 deenergizes and closes the circuit for the rotary magnet 39 at the resting contact of armature 50. Rotary magnet 39 90 operates to step the wipers into engagement with the first set of bank contacts in the selected level, and also opens the interrupter springs 67 thereby opening the holding circuit for the stepping relay 36. Stepping relay 36 deenergizes and opens the circuit 95 of the magnet 39 at armature 56. Rotary magnet 39 thereupon deenergizes and again closes the interrupter springs 67. If the trunk terminating in the bank contacts 100 74-76, inclusive, is busy, there will be ground potential on the private test contact 75 and a circuit will again be closed for the stepping relay 36 from ground on test contact 75, wiper 72, armature 58 and the resting contact, closed interrupter springs 67, 105 springs 66 through the winding of stepping relay 36 to battery. Stepping relay 36 will again operate and again close the circuit of the rotary magnet 39 at armature 56. Rotary magnet 39 will operate to step the wipers 71-73, inclusive, into engagement with the second set of bank contacts. This alternate operation of the stepping magnet 110 36 and the rotary magnet 39 will continue until the wipers 71-73, inclusive, have been rotated into engagement with the bank contacts terminating an idle trunk, an idle trunk being represented by an ungrounded private test contact. No circuit will be then closed for the stepping relay 36 when the wiper 72 is moved into engagement therewith.

It may be assumed that the trunks terminating in the first six sets of bank contacts of the connector C are busy at this 115 120 125 130

time and that the trunk terminating in the bank contacts 77-79, inclusive, is the first idle trunk. Thus the wipers 71-73, inclusive, will be rotated into engagement with 5 the bank contacts 77-79, inclusive, respectively, and will be arrested in this position. A circuit may now be traced from ground at armature 46 and the working contact, through the winding of the switching relay 37, interrupter springs 67 through the winding of the stepping relay 36 to battery. The resistance of the winding of the switching relay 37 is comparatively high and does not allow sufficient current to pass through 10 the winding to operate the stepping relay 36. Relay 37 operates, however, and prepares the signalling circuit at armature 57 and 62, places ground potential on the wiper 72 and on the bank contact 78 to make this trunk 15 test busy to other connectors, removes the shunt from around the resistance 68 and prepares circuits at armatures 59 and 60 which will be further described subsequently.

20 25 The placing of ground on the private test contact 78 also initiates the operation of the rotary line-switch RLS by completing a circuit from ground on this bank contact, conductor 92, armature 98 and the resting contact, through the winding of the line relay 95 to battery. Relay 95 operates and prepares a circuit for the switching relay 94 at armature 97, and closes a circuit for the stepping magnet 96' at armature 98'.

30 35 If the trunk accessible at the first set of bank contacts with which the wipers 91'-94', inclusive, are normally in engagement is busy, ground potential will be present on the test contact 100'. Assuming this to be the case, a circuit may be traced from this ground, wiper 92', armature 97 and the resting contact, working contact and armature 98', interrupter contacts 99' through the winding of the stepping magnet 96' to battery. Stepping magnet 96' operates, opens 40 45 its own circuit at the interrupter springs 99', and in releasing, steps the wipers 91'-94', inclusive, into engagement with the next set of bank contacts, whereupon interrupter springs 99' are closed. If the trunk terminating in this next set of bank contacts is also busy, stepping magnet 96' will again 50 55 function as described above to step the wipers another step. During this stepping operation switching relay 94 is prevented from operating by reason of the ground potential on both ends of its winding. This stepping operation continues until the switch wipers 91'-93', inclusive, are stepped into 60 65 engagement with the contacts terminating an idle trunk line, this being indicated by the absence of ground potential on the test contact with which the wiper 92' becomes engaged. No circuit will then be closed for the stepping magnet 96' and the wipers will

be arrested in that position. Furthermore, ground will be removed from the junction point of the lower terminal of the winding of the switching relay 94 and the stepping magnet 96'. Switching relay 94 will operate, its circuit being traceable from ground at the working contact and armature 58, wiper 72, bank contact 78, conductor 92, armature 97', and the working contact, through the winding of the switching relay 94, interrupter springs 99' through the winding of the stepping magnet 96' to battery. The resistance of the winding of the switching relay 94 is sufficiently high to prevent the operation of the stepping magnet 96' in series therewith. Switching relay 94, in operating, connects the wipers 91' and 93' to conductors 91 and 93 at armatures 96 and 100, respectively; opens a point in the return stepping circuit, to be described later, 70 75 at armature 99; closes a locking circuit for itself at armature 98; and places ground upon the bank contact with which the wiper 92' is engaged (and the contacts multiply connected thereto, including test contacts of 80 the connectors having direct access to the outgoing trunk in question) at armature 97 and the working contact, thereby protecting this trunk from being seized by some other rotary line switch or by connector switch also having access thereto at this time.

It may be assumed that the trunk selected by the rotary line switch RLS is a trunk comprising conductors 101 and 102. It 100 will be seen that this trunk extending to the private branch exchange is also accessible directly from the one digit connectors of groups 1-A and group 1-B in the first set of their bank contacts. This trunk was the first trunk tested by the wiper 72. At that time this trunk was assumed to be busy. In view of this assumption and further, since the rotary lineswitch RLS has selected this trunk, finding it idle, it is apparent that 105 this trunk became idle during the time of operation of the connector C and the rotary lineswitch RLS. Thus another feature of this invention becomes apparent, this being that those trunks to the P. B. X. accessible 110 directly in the banks of the one digit connectors may be tested twice, once by the one digit connector associated with the call in progress and once by the associated rotary lineswitch which was selected by that connector, after finding the trunks to the P. B. X. accessible directly in its banks busy.

When armatures 96 and 100 were operated, the signalling circuit was closed which may be traced from ground at the ringing generator G, contacts 14' closed periodically by the interrupter I, resting contact and armature 54, armature 62 and the working contact, wiper 73, bank contact 79, conductor 93, working contact and armature 100, wiper 120 125 130

93', conductor 102, armature 106 and the resting contact, through the winding of signalling relay 103, the condenser 108, conductor 101, wiper 91', armature 96 and the working contact, conductor 91, bank contact 77, wiper 71, working contact and armature 57, armature 51 and the resting contact, through the upper winding of the ring cut-off relay 25 to battery. Relay 103 is energized over 10 this circuit and closes a circuit for the signal lamp L' at armature 105. By reason of a mechanical interlocking mechanism between the armatures of relays 103 and 104, relay 103 remains operated after its first energization 15 until it is unlocked by the operation of relay 104.

In response to the lighting of the lamp L' at the private branch exchange the operator inserts the answering plug of an idle cord, 20 such as the plug P of the cord O, into the jack J of the calling trunk. Forcing the plug P into the jack J closes the springs 107 completing a circuit for the switching relay 104. As a result, relay 104 operates its armature 106, thereby disconnecting the signalling relay 103 and closing a direct current circuit for the ring cut-off relay 35 which is the same as the circuit previously traced 25 through the upper winding of relay 35 except that it now includes armature 106 and the working contact, tip and ring of jack J, tip and ring of plug P, normally closed contacts 130 and 131, armature 124 and the resting contact, and impedance coil 122. In 30 operating, relay 104 also unlocks the armature of signaling relay 103, thus allowing this relay to fall back and open the circuit of the lamp L' . Ring cut-off relay 35 operates over the previously traced circuit disconnecting 35 the signalling circuit and extending the talking connection to the operator's cord circuit at armatures 51 and 54. A locking circuit is also closed for the ring cut-off relay 35 from ground at armature 46 and the working 40 contact, armature 53 and the working contact, through the lower winding of the ring cut-off relay 35 to battery. Armature 52 is also actuated, but has no utility at this time. The operation of relay 35 also causes the 45 closure of a circuit for the back bridge relay 31 at armatures 51 and 54 and the working contacts, the lower winding of relay 31 now being connected to the grounded conductor 27 at armature 53. Relay 31 operates and at 50 armatures 42 and 43 reverses the direction of current flow supplied to the talking conductors 28 and 30 for the purpose of operating meters, etc. At armature 44 a point in the circuit of the release magnet 40 is opened, 55 and at armature 41 ground potential is applied to conductor 27 independent of armature 46, this ground extending from armature 60 and the working contact, working contact and armature 52, armature 41 and the working contact. The utility of this ad-

ditional ground supply will be described subsequently.

After inserting the plug P into the jack J, the operator throws the listening key K to the left which is the listening position, closing spring 134 and spring 135, thereby bridging the telephone sets TS across the talking conductors. She then requests the number of the subscriber with which connection is desired, and, assuming that this number is 70 that of the substation A, the operator inserts the calling plug P' into the jack J' individual to the line of the substation A, and then throws the key K' momentarily to the right which is the ringing position, closing springs 75 136' and springs 137'. The forcing of the plug P' into the jack J' separates springs 151 and springs 152, thereby removing the normal bridge including the drop signal 150 from across the line conductors 161 and 162. 80 A circuit is also closed for relay 120' from ground by way of the sleeve of jack J', sleeve of plug P' through the winding of relay 120' to battery. Relay 120' operates and opens the normal bridge through the impedance 85 122' across the answering end of the cord O and substitutes therefore the ground and battery bridge through the battery feed relay 121' through which talking current is to be supplied for the transmitter of the called 90 substation. In operating, relay 120' also closes a circuit for the supervisory lamp L^3 , 95 at armature 126'.

The bells at the substation A ring responsive to the ringing current supplied by the 100 generator R. To answer, the subscriber at the substation A removes his receiver thereby completing a circuit through the receiver and the transmitter of the substation A, over line conductors 162 and 161, tip and ring of the jack J', tip and ring of plug P', springs 105 134' and 135', key K' having been restored, springs 130' and 131', armatures 124' and 125' and their working contacts, through the upper and lower winding of the relay 121' to 110 ground and battery, respectively. Relay 121 operates and opens the circuit of the supervisory lamp L^3 at armature 127'. The extinguishing of the lamp L^3 indicates to the operator that the called subscriber has answered. The calling and called subscribers 115 may now hold conversation.

At the termination of the conversation both subscribers will replace their receivers. Replacing the receiver at the called substation A opens the circuit of the relay 121'. In deenergizing, relay 121' again closes the circuit of the supervisory lamp L^3 at armature 127'. The relighting of the lamp L^3 indicates to the operator that the called subscriber has replaced his receiver. 120

When the subscriber at the calling substation replaces his receiver, the bridge across the talking conductors is opened, thereby opening the circuit of the line relay 125 130

32. Relay 32 deenergizes and opens the circuit of the release relay 33. Relay 33 deenergizes, but being slow acting maintains its armatures attracted a short time after 5 its circuit is opened. Thus a circuit is momentarily established for the series relay 34 which may be traced from ground and armature 45 and the resting contact, armature 48 and the working contact, through the 10 winding of the series relay 34, resistance 68, through the winding of the vertical magnet 38 to battery. Resistance 68 prevents sufficient current to flow through the winding of the vertical magnet 38 to operate the 15 magnet. Series relay 34 is operated, however, and, being slow acting, remains in an energized position a short time after the release relay 33 has restored its armatures. Ground potential is removed from the conductor 29 momentarily, thereby allowing the preceding switches to restore to normal in the well known manner. The pull-down winding 11 of the plunger line switch PLS is also deenergized during this time, but the 20 plunger arm 15 is held in position by the energization of the holding winding 12 which is energized over the circuit from ground at armature 60 and the working contact, working contact and armature 52, armature 25 41 and the working contact, holding conductor 27, bank contact 21, bank spring 17, through the holding winding 12 to battery. A short time after relay 33 releases its armatures, series relay 34 drops back and again 30 places ground potential on the conductor 29, since the grounded conductor 27 is connected to conductor 29 at armature 59 and the working contact. Incidentally the pulldown winding 11 is also energized again. It will 35 be seen then that responsive to the replacing of the receiver at the calling substation, the automatic switches preceding the connector C and the plunger line switch PLS are released by the momentary removal of ground 40 from the private conductors 29 and 9, but that the connector C and the plunger line switch PLS are held operated, and that the trunk line extending to this line switch is marked busy by virtue of the replacement 45 of ground potential on the conductor 9 to prevent its being seized at this time. The plunger line switch PLS and the connector C will remain in this operated position as long as the plug P is left in the jack J. 50 The lighting of the lamp L³, however, indicates to the operator that the subscribers have finished the conversation, whereupon she will remove the plug P and P' from the jacks J and J', respectively, as soon as is 55 possible. Removing the plug P' from the jack J' again replaces the normal bridge across the subscriber's line conductors 161 and 162, including the drop signal 150, and opens the circuit of the sleeve relay 120'. 60 The circuit of the lamp L³ is opened at armature

126' and the impedance 122' is again connected across the talking conductors of the answering end of the cord O at armature 124'.

Removing the plug P from the jack J 70 opens the circuit for the back bridge relay 31 by removing the bridge including impedance 122 across the heavy talking conductors, and also opens the circuit of the switching relay 104 by permitting the separation 75 of springs 107. In deenergizing, relay 31 closes a circuit for the release magnet 40 at armature 44 and the resting contact, which circuit may be traced from ground by way of armature 45 and the resting contact, armature 48 and the resting contact, armature 44 and the resting contact, spring 63 which were closed upon the first vertical step of the connector C, through the winding of the release magnet 40 to battery. Release magnet 40 operates and releases the switch wipers in the well known manner. The restoring of armature 41 opens the holding circuit of the ring cut-off relay 35 and the switching relay 37. The current supply connections 80 to conductors 28 and 30 through the windings of relay 32 are again restored to normal by the release of armatures 42 and 43. Relays 35 and 37 deenergize and restore 85 their armatures back to normal. 95

The restoring of the connector C removes ground potential from the test contact 78, thereby opening the holding circuit for the switching relay 94 of the rotary lineswitch RLS. Relay 94 deenergizes and restores its 100 armatures back to normal. Since the wiper 94' is now in engagement with a bank contact other than its normal or home position contact, a circuit may be traced from ground, all the contacts engaged by wiper 94' except 105 the home position contact being multiply connected to ground, wiper 94', resting contact and armature 99, resting contact and armature 98', interrupter springs 99', through the winding of the stepping magnet 110 96' to battery. Stepping magnet 96' operates to rotate the wipers step-by-step until the wipers 94' again engage the ungrounded or home position. The automatic switches and the various circuits that were associated 115 with the completed connection are now restored to normal.

Had all the trunks accessible to the connector C in the selected level been busy at 120 the time the connector was hunting for an idle trunk to the private branch exchange, the rotary magnet 39 would have continued to rotate the switch wipers 71-73, inclusive, past the last set of bank contacts to the all-trunks-busy position or eleventh position. 125 When the shaft carrying the switch wipers 71-73, inclusive, is rotated to this position, a cam attached to the shaft functions to close the rotary off-normal springs 65, at the same time separating the springs 64. 130

Ground potential upon which is superimposed a busy tone is then substituted for the direct ground connected to the lower winding of the relay 32. The calling subscriber then hears the busy tone in his receiver whereupon he will replace his receiver and release the connection thus far set up in the usual manner.

If the 25 trunks accessible in the banks of the rotary lineswitch RLS had been busy when the switch wipers 91'-94', inclusive, were being rotated in search for an idle trunk, the wipers would have been rotated into engagement with the last set of bank contacts which represents the all-trunks-busy position. The 25th contact engaged by the wiper 92' is a dead contact. When the wipers are rotated to this point no circuit is closed for the stepping magnet 96' and the wipers will therefore be arrested in this position. A busy tone circuit is now traceable from the busy machine B', the wiper 91', armature 96 and the working contact, conductor 91, bank contact 77, wiper 71, working contact and armature 57, armature 51 and the resting contact through the upper winding of the ring cut-off relay 35 to battery. A busy tone current is induced in the lower winding of the ring cut-off relay 35 and flows to the talking conductor through the lower winding of the back bridge relay 31. Upon hearing the busy tone the calling subscriber will replace his receiver and try to establish the connection a little later.

Should a subscriber in the automatic exchange wish to establish a connection with the subscriber in the private branch exchange at a time when the telephone traffic to the private exchange is rather light, the connection in all probability would be extended over a more direct route, exclusive of a primary lineswitch or a rotary lineswitch. A brief description of the establishment of such a connection may now be given. Again assuming that a subscriber in the main automatic exchange wishes to establish a connection with the subscriber in the private branch exchange such as the subscriber at substation A, he will remove his receiver and dial the number reserved for the private branch exchange and again instruct the answering operator accordingly. In response to digits dialled, the connection will be extended through various switches to an idle selector which, as previously assumed, may be one contained in the sub-group No. 1. This selector operates and raises its wipers opposite the proper level of bank contacts and then rotates to hunt an idle trunk line. It may be assumed that the trunk line accessible in the first set of bank contacts is idle this time, this trunk being the one connected to the terminals 2', 3', and 4', which are connected directly to the one-digit connector C' and that this is the trunk selected. A connection is then completed over the talking loop, bank contacts 2' and 4', conductors 5' and 7', normally closed contacts controlled by armatures 42' and 43', through the upper and lower windings of the line relay 32' to battery and ground, respectively. The connector C' is the same as the connector C in all circuit details, with the exception that the conductor, such as 27, has been disconnected from the working contact of armature 41, this conductor having utility only when such a connector is accessible from a plunger line switch. The connector C' will operate responsive to the last digit to be dialled by the calling subscriber to raise its wipers opposite the proper level of bank contacts and then automatically rotate them in search for an idle trunk to the P. B. X. As previously stated, in the banks of the connector C' access is also had to trunks extending directly to the P. B. X. and to trunks terminating in rotary line switches, as is the case for connector C. It may now be assumed that the trunk terminating in the first set of bank contacts is idle. Wipers 71', 72', and 73', will therefore be arrested in engagement with bank contacts 74', 75', and 76', respectively. When this takes place, switching relay 37' operates in the same manner as did the switching relay 37, this time, however, completing a circuit for the signalling relay 103 immediately by the operation of its armatures 57' and 62'. This circuit may be traced from the signalling generator G, contacts 14' closed intermittently by the interrupter I, resting contact and armature 54', armature 62' and the working contact, wiper 73', bank contact 76', conductor 93', trunk conductor 102, armature 106 and the resting contact, through the winding of the signalling relay 103, condenser 108, trunk conductor 101, conductor 91', bank contact 74', wiper 71', working contact and armature 57', armature 51' and the resting contact, through the upper winding of the ring cut-off relay 35' to battery. Signalling relay 103 operates and lights the lamp L¹ to signal the operator. The other operations connected with the setting up of the connection to the subscriber at substation A are the same as those previously described.

Replacing the receiver at the called substation A, at the termination of the conversation again lights the lamp L³. The replacing of the receiver at the calling substation causes the release of the line relay 32' which results in the momentary energization of series relay 34' and causes the momentary removal of ground from the private conductor 6' at armature 49' since relay 34' remains operated a short time after release relay 33' drops back, as previously described. After the release of relay 34', ground is again supplied to the conductor 6'.

by way of armature 60' and the working contact, working contact and armature 52', armature 41' and the working contact, armature 59' and the working contact, resting contact and armature 49'. The trunk comprising conductors 5', 6', and 7', is therefore guarded from being seized in the establishment of another connection until the operator has again removed the plug P from the jack J. The momentary removal of ground from the holding conductor 6' is for the purpose of allowing the preceding switches to release.

The feature of the cord circuit O is primarily its simplicity. The circuits of the two-sections of the cord are practically identical. The answering end of the cord O may be used to answer calls from either the main automatic exchange or from a private branch exchange subscriber. To answer a call from a branch exchange subscriber, the operator inserts the plug P into the jack of the calling line. Relays 120 and 121 operate in the same manner as did relays 122' and 121' described above in the description of a call from a main automatic subscriber to the subscriber at substation A. The same supervision is given by means of lamp L² as was described for lamp L³.

With this cord the operator at the private branch exchange is also able to set up a tail-to-tail connection; that is, the private branch operator may set up a call to two parties and place them in talking communication with each other. For instance, a subscriber at a branch exchange substation, such as the subscriber at substation A, may call the branch operator and instruct her to place him in connection with some certain subscriber at the main automatic exchange as soon as this desired subscriber is available. The operator will then insert the plug of an idle cord such as the plug P, into the jack of an idle trunk extending to the main automatic exchange. It may be assumed that the trunk comprising conductors 101 and 102 is idle at this time and that the operator inserts the plug P into the jack J. Relay 104 operates from ground at the

springs 107, closed by the insertion of plug P into the jack J, and closes a bridge across the conductors 101 and 102 at armature 106, this bridge including armature 124 and the resting contact and the impedance coil 122. The closure of this bridge across the conductors 101 and 102 causes the initiation of the operation of the line switch RLS' at the main automatic exchange terminating the conductors 91²-93², inclusive, in the well known manner. The line switch RLS' operates to select a trunk to an idle first selector. When such a trunk is found, the selector is prepared to receive the first set of impulses. Ground potential is also placed on the conductor 92², thereby guard-

ing this trunk from being seized by a connector such as the connector C', or by a rotary lineswitch, such as the rotary line switch RLS at the automatic exchange.

After inserting the plug P into the jack J', the operator operates the key K to the right which is the dialling position, thereby closing the springs 132 and disconnecting points in the talking conductors of the cord circuit by separating springs 130 and 131. The operator then manipulates the calling device S, dialling the number of the desired party in the usual manner.

When the connection with the subscriber at the automatic exchange has been completed, the operator inserts the calling plug of the cord in use, this being the plug P' in this instance, into the jack J' and signals the subscriber at substation A in an ordinary manner. The two subscribers will be in talking communication as soon as the subscriber at substation A removes his receiver. At the end of the conversation disconnection will take place in a manner similar to that described in the previously described call. In response to the replacing of the receiver at the substation A, the supervisory lamp L³ is lighted indicating to the operator that the connection has been abandoned. In this case when the receiver is replaced at the substation in the main automatic exchange, no switches are released, the switches in the automatic exchange being under the control of the operator. As soon as the operator is notified of the discontinuation of the call, she will remove the plugs P and P' from the jacks J and J'. Removing the plug P from the jack J causes the release of the relay 104 which, at its armature 106, opens the bridge across the conductors 102 and 101 thereby causing the release of the line switch terminating the conductors 91²-92², inclusive, and also causes the release of the automatic switches in the usual manner. Ground is also removed from the conductor 92² to again mark the trunk comprising conductors 101 and 102 idle. Removing the plug P' from the jack J' restores the line 161 and 162 back to normal condition.

The invention, its features and operation, having been described, what is considered new and is desired to have protected by Letters Patent is specifically stated in the appended claims.

What I claim is:

1. In a telephone system, a calling line and a called line, a selector switch, a line switch, a connector switch, means for establishing a connection from said calling line to said called line via said selector, said line switch, and said connector, means responsive to the replacement of the receiver by the calling subscriber for releasing said selector, and means for maintaining said line switch

and said connector switch operated independent of said calling subscriber.

2. In a telephone system, a calling line and a called line, a selector switch, a line switch, a connector switch, interconnecting trunk lines each comprising two talking conductors and a private conductor, means for establishing a connection from said calling line to said called line via said selector, a trunk line, 10 said line switch, a second trunk line, and said connector, means in said connector under the control of the calling subscriber for placing a characteristic potential on the private conductors of said trunk lines to 15 maintain all of said switches operated, means responsive to the replacement of the receiver by the calling subscriber for momentarily removing the characteristic potential from the private conductors of both said trunk 20 lines to cause the release of said selector switch, means for maintaining said line switch and said connector operated, and means for replacing said potential on the private conductor of said second trunk line 25 after said selector has been released.

3. In a telephone system, a calling line and a called line, an automatic switch, a line switch, a connector, a trunk line comprising two talking conductors and a private conductor, a second trunk line comprising two talking conductors, a holding conductor and a private conductor, means for establishing a connection from said calling line to said called line via said switch, said first trunk line, said line switch, said second trunk line, and said connector, means under the control of the calling subscriber for placing a characteristic potential on the private conductors of said trunk lines for maintaining said 40 switches operated, and means under the control of the called subscriber for placing a characteristic potential on said holding conductor to prevent said line switch and said connector from releasing when the characteristic potential is removed from said private 45 conductors.

4. In a telephone system, a calling line and a called line, an automatic switch, a line switch, a connector, a trunk line comprising two talking conductors and a private conductor, a second trunk line comprising two talking conductors, a holding conductor and a private conductor, means for establishing a connection from said calling line to said 50 called line via said switch, said first trunk line, said line switch, said second trunk line, and said connector, means under the control of the calling subscriber for placing a characteristic potential on the private conductors 55 of said trunk lines for maintaining said switches operated, means under the control of the called subscriber for placing a characteristic potential on said holding conductor to prevent said line switch and said connector from releasing when the characteristic 60

potential is removed from said private conductors, and means under the control of the called subscriber for replacing said potential on the private conductor of said second trunk line to prevent the establishment of another connection to said called subscriber until said called subscriber has abandoned the first connection. 70

5. In a telephone system, a main automatic exchange, a branch exchange, trunk lines 75 interconnecting said exchanges, non-numerical hunting switches in said automatic exchange having access to said trunk lines, connector switches in said automatic exchange having access to said hunting 80 switches at certain contacts in their banks and having direct access to certain of said trunks at certain other contacts in their banks.

6. In a telephone system, a trunk line, a line switch having access to said trunk line, a connector having access to said trunk line directly and indirectly through said line switch, means for operating said connector to test said trunk line for the busy or idle 85 condition, and for operating said connector to connect with said line switch providing said trunk line is busy when tested by said connector, and means for operating said line switch to test said trunk line a second time. 90

7. In a telephone system, a calling line, a called line, a selector, a line switch, a connector, means for establishing a connection from said calling line via said selector, said lineswitch, and said connector to said called line, and means in said connector controlled over the calling line for releasing said selector and for maintaining said line switch and said connector operated. 100

8. In a telephone system, a line, means 105 including three serially related switches for extending a connection from said line, and means in the last switch for releasing the first switch while maintaining the second switch operated.

9. In a telephone system, a line, a first switch, other switches, means for extending a connection from said line via said first switch and said other switches in series, and means in one of said other switches controlled over said line for releasing said first switch and for maintaining said other switches operated. 115

10. In a telephone system, a plurality of groups of connectors, a separate group of line switches accessible to each group of connectors, a separate group of trunks accessible to each group of connectors and accessible to all of said line switches, and another group of trunks accessible only to said line switches. 120

11. In a telephone system, a plurality of groups of connectors, a separate group of trunks accessible to each group of connectors, another group of trunks accessible to some 130

of the groups of connectors, another group of trunks accessible to other of the groups of connectors, another group of trunks accessible to all of said connectors, and a separate group of line switches accessible to each group of connectors and having access to all of said trunk lines.

12. In a telephone system, a plurality of groups of connectors, a separate group of line switches accessible to each group of connectors, a separate group of trunks accessible to each group of connectors and accessible to all of said line switches at corresponding contacts, and another group of trunks accessible only to said line switches at noncorresponding contacts.

13. In a telephone system, a first switch, a second switch accessible to said first switch, a trunk line accessible to both switches, and means responsive to the dialling of a digit for establishing a connection from said first switch to said trunk line directly under certain conditions, and to said trunk line by way of said second switch under certain other conditions.

14. In a telephone system, a first switch, a second switch accessible to the first switch, a first trunk line accessible to both switches, a second trunk line accessible only to the second switch, and means responsive to the dialling of a digit for establishing a connection from the first switch to the first trunk line directly under certain conditions, and by way of the second switch under certain other conditions, and for establishing a connection from the first switch to the second trunk line by way of the second switch under certain other conditions.

15. In a telephone system, an automatic connector switch for establishing a connection from a calling to a called party and having a plurality of rows of bank contacts, means directly controlled responsive to the dialling of the last digit of a telephone number for positioning the switch into selective relation with the row of contacts corresponding to the digit dialled, means responsive to the positioning of said switch on any row of contacts for causing the switch to automatically select an idle contact in the selected row providing one is idle, means for giving the calling party a busy signal providing all the contacts in the selected row are busy, and battery feed bridges in said switch for feeding talking current to the calling and called lines.

16. In a telephone system, a trunk terminating in an automatic switch, said trunk comprising talking conductors, and two release conductors, means for seizing said trunk, means in said switch responsive to the seizure of said trunk for applying a characteristic potential to one of said release conductors, means for operating said switch to extend a call, means in said switch responsive to the answering of the call for applying a characteristic potential to the other release conductor, and means responsive to the replacement of the receiver on the calling line for momentarily removing the potential on one of the release conductors.

In witness whereof, I hereunto subscribe my name this 14th day of January, A. D., 1926.

CLARENCE E. LOMAX.
